HOOPING OF THE STACKS OF BLAST FURNACES

Filed April 1, 1927

UNITED STATES PATENT OFFICE.

ARTHUR JULES FRANÇOIS JOSEPH COUSIN, OF SERAING, BELGIUM, ASSIGNOR TO
SOCIÉTÉ ANONYME JOHN COCKERILL, OF SERAING, BELGIUM.

HOOPING OF THE STACKS OF BLAST FURNACES.

Application filed April 1, 1927, Serial No. 180,108, and in Belgium April 8, 1926.

My invention relates to improvements in the hooping of the stacks of blast furnaces.

As it is well known, the hooping as actually effected comprises a series of hoops, each 5 of these hoops surrounding the stack on all its periphery.

This system of hooping presents many inconveniences.

Firstly it wants of rigidity in the vertical 10 direction, and does not avoid the sinking of the masonry. Moreover the breakage of one hoop exerts its influence on the whole periphery of the stack by depriving the set of bricks which is thus exposed of all support whereby the exposed bricks may be dislocated by the least explosion until the hoop 15 has been repaired.

In order to avoid these inconveniences it 20 has been suggested to surround the whole stack with a continuous covering of sheet iron. This sheeting has not given good results in view of the fact that in this case the masonry is inaccessible and cannot be repaired, which constitutes a great drawback when the quality of the coke necessitates frequently lateral soundings or local 25 repairs of certain parts of the stock.

My invention has for its object to secure 30 the rigidity and the safety of the systems in which it is made use of a continuous covering, and at the same time to maintain the advantages of the ordinary system of hooping with regard to the accessibility of the stack.

35 With this object in view my invention essentially consists in the special arrangements and combinations of parts hereinafter fully described and pointed out in the appended claims.

40 Referring to the annexed drawings:

Figs. 1 and 2 are, respectively a vertical cross sectional view and a front view of the system of hooping according to the invention.

45 Fig. 3 is a horizontal cross section at the level of one hoop.

On these drawings, B are the hoops which are arranged around the stack at different heights and which are connected by upright 50 posts connected at the lower part to the bracket rim M. These upright posts A, the number of which is 6 or 8 are very resistant and extend to the upper part of the stack.

They divide each hoop in 6 or 8 independent segments and are constituted by a steel plate p the thickness of which is about 2 to 4 cm. and on which two angle irons are riveted so as to form two parallel ribs C to which the ends of the segments B are fixed. To this end, the ribs C are provided 60 with holes a and the ends of the segments are provided with bolts b having a screwed end engaging in the said hole, the bolts b being maintained through nuts d. As it will be easily understood, these bolts b could be 65 replaced by keys or any other convenient means. The rigidity of the ribs C is obtained by cross pieces r.

The holes provided in the ribs C may be disposed so that the segments will be 70 in alignment with each other or in a staggered relation.

What I claim is:

1. In a system of hooping for the stacks of blast furnaces in combination with the 75 masonry of the stack upright posts arranged on the said masonry, segments of hoops disposed horizontally at different levels on the masonry, and means whereby the said segments of hoops are connected to the said 80 upright posts.

2. In a system of hooping for the stacks of blast furnaces, in combination plates arranged vertically on the masonry of the stack, angle irons fixed on the said plates, 85 segments of hoops disposed horizontally on the masonry and means whereby the said segments of hoops are connected to the said angle irons.

3. In a system of hooping for the stacks of blast furnaces in combination, plates arranged vertically on the masonry of the stack, two parallel angle irons fixed on the said plates and extending vertically from the upper to the lower part of the stack, 95 segments of hoops disposed horizontally on the masonry holes in the said angle irons, bolts engaging on the said holes whereby the said segments of hoops are connected to the said angle irons fixed on the said vertical plates and means whereby the rigidity 100 of the said parallel angle pieces is secured.

4. In a system of hooping for the stacks of the blast furnaces in combination plates arranged vertically on the masonry of the 105 stack, two parallel angle irons fixed on the

said plates and extending vertically from the upper to the lower part of the stack, segments of hoops disposed horizontally on the masonry, holes in the parallel angle irons, bolts engaging in the said holes, whereby the said segments of hoops are connected to the said parallel angle irons and

cross pieces whereby the rigidity of the said parallel angle irons is secured. In testimony whereof I have affixed my ¹⁰ signature.

ARTHUR JULES FRANÇOIS JOSEPH COUSIN.
